FREDERICK T. MOORE, OF EAST HARTFORD, CONNECTICUT, ASSIGNOR TO COLT'S PATENT FIRE ARMS MANUFACTURING CO., OF HARTFORD, CONNECTICUT, A CORPORATION OF CONNECTICUT

REVOLVER

Application filed September 23, 1930. Serial No. 483,797.

With some types of ammunition commonly used in revolvers there is a slight swaging action which takes place upon firing, when the bullet is forced through the forward end of the cartridge chamber and into the barrel. Frequently, the bullets are covered or sheathed with copper or other metal and, as the result of the swaging action, fragments of this sheathing together with particles of lead are detached from the bullets and are subjected to the action of the gasses of explosion. Some of these fragments or particles are forced outward through the narrow space between the rear face of the barrel and the front face of the cylinder. In accordance with prior practice the front face of the cylinder has been a single plane surface, and the result has been that some of the particles thus discharged by the gases have been deposited on the said surface, the deposits taking the form of rings surrounding the several chambers. This phenomenon is commonly known as "leading", and it is objectionable from the standpoint of appearance, and is further objectionable in that it would, if allowed to continue sufficiently, eventually interfere with the rotation of the cylinder and hence with the functioning of the revolver.

The object of the present invention is to provide a revolver so constructed as to avoid the difficulties which have been above described.

In the accompanying drawings I have shown two embodiments of the invention, but it will be understood that the drawings are intended for illustrative purposes only and are not to be relied upon as limiting or defining the scope of the invention, the claims forming a part of this specification being relied upon for that purpose.

Of the drawings:

Fig. 1 is a side view of a revolver embodying the invention.

Fig. 2 is a detail view showing the front of the cylinder.

Fig. 3 is a fragmentary sectional view of the cylinder taken along the line 3—3 of Fig. 2 and also showing the rear end of the barrel.

Figs. 4 and 5 are views similar respectively

to Figs. 2 and 3, but showing an alternate embodiment of the invention.

Referring to the drawings, 1 represents the frame of the revolver, 2 the barrel, 3 the rotatable cylinder, 4 the hammer and 5 the trigger. In general these parts may be of any usual or preferred construction, and it will be unnecessary to describe in detail any of the said parts other than the cylinder, as it is to the cylinder that my present invention primarily relates.

As shown clearly in Figs. 2 and 3, there are formed in the front face of the cylinder, annular grooves 6 surrounding the respective cartridge chambers 7 and spaced therefrom to leave very narrow annular surfaces 8 immediately surrounding the said chambers. The external diameter of each annular surface 8 is no greater than the external diameter of the rear end portion of the barrel 2, and is preferably considerably smaller, as clearly shown in Fig. 3. The cylinder 3 is rotatable with respect to the frame 1 in the usual way so that during the normal firing of the revolver the several chambers 7 are brought successively into register with the bore of the barrel. The mounting of the cylinder is such that the annular surfaces 8 come into very close proximity with the rear face of the barrel, thus reducing to a minimum the space available for the gases of explosion to escape between the barrel and the cylinder. It will be apparent that, while the surfaces 8 come into very close proximity to the rear face of the barrel, the grooved portions 6 of the cylinder face immediately surrounding each surface 8 are in a different plane and are separated from the plane of the rear face of the barrel.

The construction shown in Figs. 4 and 5 differs from that shown in Figs. 2 and 3 solely in that the entire front face 6^a of the cylinder, except for the annular surfaces 8, is located in a plane at the rear of the plane of the said surfaces.

I have found that by providing only the very narrow annular surfaces 8 in close proximity to the rear face of the barrel, I am enabled to largely, if not in fact entirely, avoid the described objectionable metallic

5 deposits on the front of the cylinder. It is impossible to state with certainty in what way my improved construction modifies the action of the gases so as to avoid the objectionable leading; but I believe that the improved result is due to the fact that the radially moving gases are allowed to expand more quickly thus creating a turbulence which prevents the undesirable deposit of

10 metal.

15 It will furthermore be observed, that with my improved construction, even if a slight degree of "leading" should occur, it would be much less objectionable, as it would be in the 15 grooves or on the offset surface 6^a where it could do no harm.

What I claim is:

20 1. A revolver having at the extreme rear of the barrel an annular substantially flat face immediately surrounding the bore and having at the front of the cylinder narrow annular substantially flat surfaces immediately surrounding the respective cartridge chambers, which latter surfaces are of a 25 diameter no greater than that of the aforesaid rear face of the barrel and are adapted upon normal rotation of the cylinder to be successively positioned in register with and in close proximity to the said rear face, the 30 portions of the front face of the cylinder immediately surrounding the said annular surfaces being at a different plane so as to be separated from the said rear face of the barrel.

35 2. A revolver having at the extreme rear of the barrel an annular substantially flat face immediately surrounding the bore and having in the front face of the cylinder annular grooves surrounding the respective cartridge 40 chambers and spaced therefrom to leave narrow annular substantially flat surfaces immediately surrounding the chambers, which latter surfaces are of a diameter no greater than that of the rear face of the barrel and 45 are adapted upon normal rotation of the cylinder to be successively positioned in register with and in close proximity to the said rear face of the barrel.

50 In testimony whereof I have hereunto set my hand this 11th day of September, 1930.

FREDERICK T. MOORE.
